UNITED STATES PATENT OFFICE.

BRODEHURST ELSEY, OF INDIANAPOLIS, INDIANA.

DESIGN FOR A DISPLAY TAG.

• 60,610.

Specification for Design. Patented Mar. 14, 1922.

Application filed May 5, 1921. Serial No. 467,214. Term of patent 14 years.

To all whom it may concern:

Be it known that I, BRODEHURST ELSEY, a citizen of the United States, residing in the city of Indianapolis, county of Marion, and State of Indiana, have invented a new, original, and ornamental Design for a Display Tag, of which the following is a specification, reference being had to the accompanying drawing, forming part thereof.

Fig. 1 is a plan view and Fig. 2 is a side view of the tag, showing my new design.

I claim:

The ornamental design for a display tag, as shown.

BRODEHURST ELSEY.
